(57) **CLAIM**

The ornamental design for a control lever, as shown and described.

DESCRIPTION

FIG. 1 is a perspective view of a control lever showing my new design;

FIG. 2 is a front view thereof;

FIG. 3 is a side view thereof;

FIG. 4 is a side view of the body of the control lever; and, FIG. 5 is a perspective view of the body of the control lever. The cover that appears in FIGS. 1 through 3 is not shown in FIGS. 4 and 5 for convenience of illustration.
